UNITED STATES PATENT OFFICE.

HERMANN FISCHER, OF BOSTON, MASSACHUSETTS, ASSIGNOR TO TOWER MANUFACTURING CORPORATION, OF BOSTON, MASSACHUSETTS, A CORPORATION OF MASSACHUSETTS.

SOUND AMPLIFIER.

Application filed February 4, 1926. Serial No. 85,828.

The object of the present invention is to provide a sound amplifier comprising a resonator and means for operatively connecting the resonator and the diaphragm at a point or points spaced from the axis of the diaphragm. I have discovered that the connection of a resonator, as for example a cone type resonator, with a diaphragm, through a needle or similar connection with the centre of the diaphragm, acts to damp and prevent satisfactory vibration of the diaphragm. I have also discovered that when the point or points of connection between the resonator and the diaphragm is substantially spaced from the centre of the latter, the damping is prevented.

In the vibration of a diaphragm secured at its periphery, the point of greatest vibration is at its axis, or in line with the magnet poles. But the subjection of the diaphragm at that point to a load enables the maximum resistance of the load to the vibrations. The ideal condition in amplification is to secure maximum force with minimum degree of movement in the vibrations of the diaphragm which are to be transmitted to the resonator through a mechanical member. By placing the point or points of connection between the resonator and the diaphragm at a substantial distance from the centre of the diaphragm, the ring or other means for clamping the diaphragm at its periphery serves as a fulcrum for the diaphragm and the force exerted on the diaphragm by the magnets operates the diaphragm as a lever relatively to the connecting member between the resonator and the diaphragm, and thus whilst the vibrations from the diaphragm are taken at a point where they are substantially less in length of movement than at the centre, they have greater force and are better for proper vibration of the resonator.

The invention will be used in connection with a diaphragm which may be electrically vibrated as in the case of a radio loud speaker or a diaphragm which is mechanically vibrated as in the case of a phonograph.

The invention will be understood by reference to the accompanying drawing, in which—

Figure 1 illustrates in sectional side elevation a standard, a loud speaking unit and

an embodiment of the invention as applied to a cone type resonator;

Figure 2 is a sectional elevation showing a modified form of the invention applied to a cone type resonator, on the line 2—2, Figure 3;

Figure 3 is a plan view of the structure illustrated in Figure 1;

Figure 4 is a view in vertical section of a modified form of the device on the line 4—4, Figure 5, and

Figure 5 is a plan view of the same;

Figure 6 is a plan view of a blank combining a diaphragm with the connecting means for a resonator, and

Figure 7 is a vertical section through part of a cone type resonator showing a modified form of connection between the same and a diaphragm.

Referring to Figure 1, A represents a standard having at its upper end a chamber 1 to receive the magnet 2, the electrical connections leading to the magnet elements passing through the standard to the base in the usual manner. The diaphragm acted upon by the magnet is indicated at 3 clamped between an annular shoulder 4 of the standard top and a securing ring 5 which is threaded on the standard. Annularly arranged and spaced from the centre of the diaphragm 3 are a plurality of webs 6, which lead to a conical head 7. The webs 6 may be constructed separate from the diaphragm and head 7 and may be welded thereto, or they may be formed integrally with one of the two members and brazed, soldered or otherwise secured to the second member. In Figure 6 I have shown the webs 6 as formed integrally with the diaphragm 3.

Projecting at the apex of dome 7 is a threaded stem 8. This stem may pass through an aperture formed in the resonator 9, a cap 10 may be placed over the resonator and upon stem 8 and a nut 11 may be used to clamp the said associated members together so as to firmly hold dome 7 in contact with the resonator. In order to prevent such edge vibration of the webs as will produce a noise, they may be covered with a sound absorbing material such as rubber, felt or the like indicated at 12. In the aforesaid combination the diaphragm 3 transmits

its vibrations to the resonator 9 through connections which are spaced from the axial point of the diaphragm, a ring of connections being employed. Of course the form and arrangement of the connections may be widely varied from the construction shown in Figure 1 and the modifications illustrated in the drawings.

In Figures 2 and 3 I have shown the connection intermediate the resonator and the diaphragm form as a ring 12 having transversely extending connecting members 13 for connection to the resonator and like members 14 for connection to the diaphragm.

15 In the modification illustrated in Figure 7, the connecting member is coniform and is provided at its point of minimum diameter with a plurality of connection members 15 for application to the resonator 16, and 20 at its base with a plurality of connecting members 17 for application to the diaphragm shown in dotted lines at 18. In the construction shown in Figures 4 and 5 I apply a plurality of webs 19, which at their 25 tops may be bent angularly as at 19^a for connection to the resonator 20. At their base the webs may be formed with feet as at 21 for connection to the diaphragm 22 indicated in dotted lines.

30 It will be understood that the resonator may be formed in any desired shape. It may be flat, conical or other shape in cross section, and it may be round or rectangular or other peripheral shape. It will be also 35 understood that any suitable number of connecting members may be employed intermediate the diaphragm and the resonator and that these connecting members may be formed as pins, webs, rings and in various 40 forms and shapes other than those illustrated in the drawings.

Having described my invention what I claim and desire to secure by Letters Patent is as follows:—

45 1. In combination with a coniform resonator having a free edge, of means for supporting and vibrating the resonator, comprising a diaphragm, means for vibrating the diaphragm and spaced webs rigidly con-

nected to and extending transversely of the 50 diaphragm, said webs being connected to the resonator.

2. In combination with a resonator of means for supporting and vibrating the same, comprising a diaphragm, having peripherally projecting fingers, a plurality of the fingers being of major length and a plurality being of minor length, the major length fingers being bent at an angle and rigidly connected to the resonator, and a magnet device 55 for vibrating the diaphragm, said device being adapted to hold the diaphragm about its periphery by clamping the projections of minor length.

3. Sound amplifying apparatus constructed in accordance with claim 2, in combination with sound absorbing means carried by the spaced projections of major length.

4. In sound amplifying apparatus, a diaphragm, a resonator, and means for operatively connecting the two, comprising spaced webs secured to the diaphragm near its periphery and extending transversely thereof.

5. In sound amplifying apparatus, a diaphragm, a magnet for vibrating the diaphragm, a resonator having a free edge, and means for both supporting and transmitting vibration to the resonator comprising a carrier for the resonator and a plurality of webs intermediate the diaphragm and 75 the carrier and supporting the latter, the vibrations of the diaphragm being transmitted to the carrier through said webs.

6. In sound amplifying apparatus, a diaphragm, a magnet for vibrating the diaphragm, a resonator having a free edge and means for both supporting and transmitting vibration to the resonator, comprising a rigid metallic carrier for the resonator having a marginal edge and means for supporting the carrier about its marginal edge, said means being connected with the diaphragm and said means transmitting the vibrations of the diaphragm to the carrier and the resonator.

In testimony whereof, I have signed my name to this specification.

HERMANN FISCHER.
